(57) **CLAIM**

The ornamental design for an analysis instrument, as shown and described.

DESCRIPTION

FIG. 1 is a front, top, and right perspective view of an analysis instrument;

FIG. 2 is a rear, bottom, and left perspective thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines depict portions of the analysis instrument that form no part of the claimed design.
